LAMP SHADE

George Henry Deitsch, Niles, Mich., assignor to
National Standard Company, Niles, Mich., a
corporation of Michigan

Application October 13, 1934, Serial No. 748,207

4 Claims. (Cl. 240—108)

This invention relates to articles such as lamp shades, and has to do both with an improved construction of such articles and with a simple and effective method of making them.

5 An object of the invention is to make a shade or the like of pleasing appearance which is light in weight and inexpensive to manufacture. It is a further object to do this in a manner providing a pattern (preferably of braided wire) 10 outlined against a material of contrasting color, and moreover I prefer to make the exterior and interior of the shade of different colors which not only add to the appearance but which also cooperatively determine the color of the light 15 transmitted through the shade.

In one desirable arrangement, a wire framework is formed, preferably of wire braid arranged in a pattern providing relatively wide spaces for the transmission of light. Upon this 20 framework is superposed a series of films or layers, of suitable lacquer or enamel transparent or translucent materials, the outermost one of which is preferably transparent and colorless and envelopes and protects the wire of the framework without substantially altering its appearance.

This leaves the wire outlined and contrasted against the color of the next film or layer, which shows through in the spaces of the pattern, giving 30 a novel and very pleasing exterior appearance in a shade which can be made at a very low cost as compared to the usual silk-lined shade. The pattern is especially effective where the wire of the framework is braided, being woven or otherwise arranged to give the desired pattern.

The outermost film is preferably formed of a cellulose compound, for example containing nitrocellulose, dissolved in a considerable amount of solvent. As the solvent is driven off in drying 40 this first film, the material is stretched out to give an extremely thin but tough film under tension, supported by the wire framework. This makes the wire stand out prominently in a very pleasing manner. I prefer to use for the second 45 and intermediate coats or films a material such as cellulose acetate with a comparatively small amount of solvent, with a pigment or dye or a water color, applied for example by spraying or brushing in a manner such that it can be dried 50 by driving off the relatively small amount of solvent before the latter attacks or injures the first film. The last or innermost coat or film is preferably of a relatively refractory paint or the like capable of withstanding the heat inside the 55 lamp.

If it is desired to give the innermost film or layer a different color, this will determine the color of the interior of the shade, while the two colored films cooperatively determine the color of the light transmitted through the shade. It 5 is also feasible to vary the color of the light so transmitted by providing a suitably colored intermediate film which is not visible by reflected light either from the exterior or the interior.

I prefer to make the necessary framework by 10 providing inner and outer supporting rings one of which, preferably the inner one, is formed with an annular series of slots. The braid or other wire may then be arranged in loops, the center of each loop being arranged in one of the 15 slots with the ends diverging therefrom, and interwoven or otherwise interconnected with the other loops in a suitable pattern, and with its ends soldered or otherwise secured to the unslotted ring. I prefer to conceal these ends by 20 means such as an encircling ring of braided wire or other material.

The above and other objects and features of the invention, including various novel constructions and desirable specific features and method 25 steps, will be apparent from the following description of the illustrative construction shown in the accompanying drawings, in which:

Figure 1 is a side elevation, partly broken away to show the attached ends of some of the 30 loops of braided wire;

Figure 2 is an enlarged partial elevation of the encircling ring of braided wire which conceals the attached ends of the described loops;

Figure 3 is a partial elevation showing the 35 attaching of the loops to the inner slotted ring;

Figure 4 is a partial section, on the line IV—IV of Figure 3, showing how the braid passes through one of the slots;

Figure 5 is a section on the line V—V of Figure 2, but on a larger scale, and showing the structure of the encircling ring; and

Figure 6 is a partial section through the finished shade, on the line VI—VI of Figure 3, showing the arrangement of the above-described 45 superposed films or layers of transparent or translucent material.

The shade is illustrated as mounted on a suitable support 10 carrying an electric bulb 12 arranged inside the shade, in such a manner that 50 part of the light from bulb 12 is reflected upwardly and part of it is transmitted through the shade.

The shade is preferably built up on a light but strong framework of braided wire or the like, the 55

braids being interwoven or otherwise connected in a desired pattern. The wire of the braid is first cleaned and plated, in any desired manner, both for ornamentation and protection.

5 In the particular arrangement illustrated, a number of loops 14 of wire braid are so interwoven, each with its center passing through one of an annular series of slots 16 in an inner ring 18, of suitable metal. The halves of each loop 10 diverge from the slot and interweave as desired with the other braids, the ends being soldered or otherwise secured to an outer and larger ring 20 forming the rim of the shade.

I prefer to conceal the attached ends, and the ring 20, by an ornamental encircling ring 22, shown as woven from wire braids 24. The ring 15 18 is ordinarily concealed by being clamped between the support 10 and the bulb 12.

According to an important feature of the invention, instead of the usual silk lining, I form 20 my novel shade with superposed films or layers 26, 28, 30, 32, etc., of suitable transparent or translucent material such as lacquer, thin enamels or paints, and the like. These films are shown 25 on a much exaggerated scale in Figure 6.

The outer film 26 is preferably of one of the 30 numerous transparent and substantially colorless but very tough lacquers made of cellulose or artificial resinous material, for example a solution of nitrocellulose in butyl lactate. An example might be:

106 lbs. cellulose nitrate, 27 gallons toluol, 13½ 35 gallons butyl acetate, 4½ gallons butyl alcohol, and 2 gallons dibutyl phthalate.

If necessary, more butyl lactate is added until the solution is as thin as will form a continuous film supported by the framework and bridging the spaces therein when the framework is dipped into the solution. When such a film is dried by 40 driving off the solvent, it becomes extremely thin but tough, stretching out and drying under tension. This makes the wire stand out prominently, and lends emphasis to the pattern made by the wire. Various other lacquers are commercially known, and may be used, consisting of 45 various mixtures of cellulose nitrate or acetate, with a plasticizer or a resin or both in some cases, and with a solvent such as butyl acetate, butyl alcohol, ether, or acetone, or a mixture. I find 50 the cellulose nitrate or acetate solutions with butyl lactate as the solvent, to be also very good for my purpose.

The framework is preferably dipped into this 55 material, as described, which therefore not only bridges across and closes the relative wide spaces in the pattern between the sections of braid 14, but also incloses and protects the wire strands in the braid without substantially altering its appearance.

60 This film is then dried, or heated, or otherwise treated to drive off the solvent, and to form it into a permanent extremely thin but tough transparent film stretched under tension upon the wire of framework and which may serve as a support for the other films 28, 30, 32, etc. These 65 inner films therefore need not necessarily be of material having any great tensile strength.

The second film 28 is preferably of the color 70 desired for the exterior of the shade, and shows through the transparent outer film 26. As film 28 underlies the braid 14, the braid is outlined against this color in a pattern determined by the arrangement of the braid, and shown with relatively wide intervening spaces in which the color of film 28 shows through. This gives a very

pleasing exterior appearance to the shade. I prefer to form this second film by spraying or brushing upon the inside of film 26 a solution containing, with a cellulose compound such as cellulose acetate and a pigment or a dye or even 5 a water color, a relatively small amount of solvent. This material therefore dries, by the driving off of the solvent, so quickly as not to attack or injure the film 26.

The innermost film 32 may be of a different 10 color, preferably in pleasing contrast to the color of film 28, and is preferably of a relatively refractory material such as a paint or enamel to withstand the heat inside the lamp. A fast drying clear enamel containing a pigment of the desired 15 color may be used. The color of film 32 determines the color of the upwardly-reflected light, as well as the color of the shade when viewed from the interior.

There may also be one or more intermediate 20 films 30. These are not normally visible from either the exterior or the interior of the shade, but they do cooperate with films 28 and 32 in cooperatively determining the color of the light transmitted through the shade. Film 30 may 25 be of solid color, or it may be in the form of a pattern or picture which becomes visible only by light passing through the shade. It may be of cellulose material, or merely a suitable dye dissolved in butyl lactate or the like, and sprayed 30 in place. However, I prefer to use a fast drying clear enamel having added thereto a small amount of coaltar dye of the desired color.

One quick-drying clear enamel paint suitable 35 for use as described above may be made by combining 100 lbs. Amberol (F7), 10 gallons China wood oil, 5 gallons two and one-half hour linseed oil, 3 lbs. fused lead resinate, and 35 gallons of a suitable mineral thinner. The Amberol and China wood oil are heated at 540° F., the temperature being raised to 560° F. just before the mixture is removed from the fire; the linseed oil and lead resinate are added and the mixture allowed to stand some time at 500° F.; and the mixture is then cooled to 450° F., at 45 which temperature the thinner is added.

While one illustrative embodiment has been described in detail, it is not my intention to limit the scope of the invention to that particular embodiment, or otherwise than by the terms of 50 the appended claims.

I claim:

1. A lamp shade or the like comprising an unjointed wire framework arranged in a pattern, a film of transparent material overlying said pattern and enveloping and protecting the wire of said framework without substantially altering its appearance from the exterior of the shade, a film of colored material superposed on the inner surface of the first film and showing 60 through the first film as determined by said pattern and in contrast to the wire of said pattern, and a third film of colored material arranged on the inner side of the second film and determining the color of the shade when 65 viewed internally, said two colored films cooperatively determining the color of the light transmitted through said shade.

2. A lamp shade or the like comprising inner and outer rings, one of which has an annular series of slots, and wire braid woven in a pattern of a series of loops each passing through one of said slots at its center and diverging therefrom and having its ends secured to the unslotted ring, together with superposed films of light- 75

transmitting material bridging the spaces in said pattern and with the outermost film enveloping and protecting said wire braid.

5. A lamp shade or the like comprising inner and outer rings, the inner and smaller one of which has an annular series of slots, and wire braid woven in a pattern of a series of loops each passing through one of said slots at its center and diverging therefrom and having its ends secured to the outer and larger ring, and a braided wire ring encircling said outer ring and concealing the ends of said loops attached thereto, together with superposed films of light-transmitting material bridging the spaces in said pattern 10 and with the outermost film enveloping and protecting said wire braid.

10. A lamp shade or the like comprising an un-

jointed wire framework and superposed films of different colors, the outer one of which is transparent and envelopes and protects the wire of the framework while leaving the wire fully exposed as a pattern outlined against the color of 5 a different film underlying the outer film, said different film and the innermost film being of different film and the innermost film being of different colors determining the exterior and interior colors of the shade and one of the intermediate films being of another color not visible 10 by reflected light either from the exterior or interior of the shade and which combines with said other two films of different colors cooperatively to determine the color of the light transmitted through said shade. 15
